CLAIM

The ornamental design for a slipper with adjustable heel strap, as shown and described.

DESCRIPTION

FIG. 1 is a perspective view of a slipper with adjustable heel strap, showing our new design, with the strap in forward position.

FIG. 2 is a top plan view thereof.

FIG. 3 is a bottom plan view thereof.

FIG. 4 is a side elevation view thereof.

FIG. 5 is a side elevation view thereof, opposite the side elevation view of FIG. 4.

FIG. 6 is a front elevation view thereof.

FIG. 7 is a rear elevation view thereof.

FIG. 8 is a perspective view of a slipper with adjustable heel strap of FIG. 1 with the strap in a rearward position.

FIG. 9 is a top plan view thereof.

FIG. 10 is a bottom plan view thereof.

FIG. 11 is a side elevation view thereof.

FIG. 12 is a side elevation view thereof, opposite the side elevation view of FIG. 11.

FIG. 13 is a front elevation view thereof; and,

FIG. 14 is a rear elevation view thereof.

The broken lines in the drawings are included for purposes of illustrating portions of the slipper that form no part of the claimed design.

The claimed device is used as an item of footwear.
